JOHN C. MINOR, OF NEW CANAAN, CONNECTICUT, ASSIGNOR TO WILLIAM WHARTON, JR., & COMPANY, INCORPORATED, OF EASTON, PENNSYLVANIA, A CORPORATION OF PENNSYLVANIA

MANUFACTURE OF GAS CYLINDERS

Application filed April 25, 1930. Serial No. 447,313.

The invention relates to cylinders for compressed gases or gaseous fluids and more particularly to cylinders constructed of seamless drawn metal, that is to say, cylinders formed 5 from a billet by piercing, extrusion and drawing. According to that method, the bottom of the cylinder is closed under the steps of piercing and extrusion, and after the final drawing the top is formed by forging with necking hammers or by spinning, which closing operation adds materially to the cost of 10 manufacturing. Moreover, a cylinder so formed is impractical for certain uses. For example in the case of acetylene where a 15 solid packing is used inside the cylinder, the cylinder should be open to receive the packing and then closed.

Hence, the objects of my invention are to adapt seamless drawn cylinders for certain 20 uses for which heretofore they were impracticable and generally to lessen the cost of manufacture of such cylinders.

The nature of the invention consists in providing a seamless drawn cylinder having 25 a die formed top or valve-receiving portion, the other end being fully open for the reception of packing and the like and being ultimately closed in any approved manner.

The invention in its preferred form is illustrated in the annexed drawing, wherein

Figure 1 is a longitudinal sectional view of a seamless drawn cylinder whereof the top is formed in the initial cupping operation.

Fig. 2 is a similar view showing the completion of the next step of drilling and tapping the top for the accommodation of the usual valve.

Fig. 3 shows the bottom closed as, for example, from the result of spinning.

Fig. 4 shows a cylinder with a bottom welded to place.

In the practice of my invention, the cylinder 5, under the die forming operation of piercing and extruding or cupping, is provided with a solid or integrally closed top 6. It is a merit of the invention that the top 6 is formed with an inwardly directed axial projection or boss 7 to insure adequate seating depth of the usual valve when the top is 50 drilled and tapped as at 8.

Evidently, by constructing a cylinder with a die formed top and with its other end open the full diameter of the cylinder, I greatly reduce the cost of manufacture in that I obviate the old practice of forging and necking, and 55 withal, I provide a cylinder for general usage.

The closing of the open or ultimate bottom end of the cylinder is a matter of expediency or choice. For example, referring to Fig. 3, 60 a bottom 9 is shown which may result from spinning. The preferred practice, however, at any rate in the case of packed acetylene or with liquefied petroleum gas, is shown in Fig. 4 in which 10 represents a dished head 65 that is welded to place.

Having described the invention, what is claimed is:

The method of forming seamless drawn metal cylinders, which consists in forming 70 from a billet by piercing and drawing a cylinder having a closed head portion characterized by its thickness with relation to the side wall section and by an inwardly directed axial boss, the other end of the cylinder being open its full diameter, boring and tapping 75 said closed head portion, including its co-extensive boss, for the reception of a valve, and ultimately closing the open end of the cylinder.

In testimony whereof I affix my signature.

JOHN C. MINOR.
